UNITED STATES PATENT OFFICE.

MAX LANGER, OF BERLIN-HERMSDORF, GERMANY, ASSIGNOR TO SIEMENS & HALSKE AKTIENGESELLSCHAFT, WERNERWERK, OF SIEMENSSTADT, NEAR BERLIN, GERMANY.

TELEPHONE SYSTEM.

Application filed April 30, 1926, Serial No. 105,648, and in Germany July 11, 1925.

The invention relates to telephone systems in which connections are set up between incoming and outgoing lines.

When calls are set up in such systems, the whole traffic may be disturbed if more than two lines are interconnected, thus effecting the so called double connections. These faults are especially liable to occur, for instance, at operators' positions, over which connections are set up between incoming and outgoing lines over cordless routes, for examples, by merely pressing a key.

The object of the invention is to avoid such faults by absolutely preventing double connections, this being achieved by providing the incoming and outgoing lines with testing devices, which prevent the connecting up of one or more incoming or outgoing lines to an existing connection.

As an example of the invention, the drawing shows a circuit for selectively setting up connections between three incoming and three outgoing lines. For example if the incoming line 2 is to be connected to the outgoing line 1, the operator actuates a key, thereby switching over its contacts 1^a—4^a. At contact 3^a of this key, the following circuit is established for the test relay P¹: earth, windings I and II of P¹, lead a¹, contact 3^a, resistance W¹, battery, earth. At the contact 5^{a1}, the relay P¹ short circuits its high resistance winding I, thereby in known manner marking the incoming line 2 engaged. At the contacts 6^{a1} and 7^{a1} the outgoing line 1 is connected over the leads a¹ and b¹ to the contacts 1^a and 2^a of the connecting key. The contact 4^a closes the following circuit for the test relay Q¹ of the incoming line 2: earth, windings I and II of relay Q¹, contact 4^a, lead d¹, resistance W², battery, earth. At its contact 8^{a1} the relay Q¹ short circuits its high resistance winding I, thus marking the outgoing line 1 engaged. At the contacts 9^{a1} and 10^{a1} the incoming line 2 is switched through over the contacts 1^a and 2^a and the leads a¹ and b¹ to the outgoing line 1.

If the connecting operator, by switching over the contacts 11^{a1}—14^{a1}, attempts to connect the outgoing line 3 to the connection existing between the incoming line 2 and the outgoing line 1, the test relay P² belonging to the outgoing line 3 cannot operate, because its serially connected windings I and II are connected over the lead c^a and the contact 13^{a1} in parallel with the low resistance winding II

of the energized test relay P¹. The relay P² now prevents the switching through of the outgoing line 3, because its contacts 15^{a2} and 16^{a2} are not closed. The busy signal can now be given to the operator in any desired manner, whereupon she returns the contacts 11^{a1}—14^{a1} to their normal position.

If the operator attempts to connect an incoming line, for example the incoming line 1, to the existing connection between the incoming line 2 and the outgoing line 1, and for this purpose presses the key whereby the contacts 17^{a2}—20^{a2} are closed, the test relay Q² of the incoming line 1 is then connected in parallel with the low resistance winding II of the relay Q¹ over the contact 20^{a2} and over the lead d¹. Since the windings I and II of the relay Q² are shunted by the low resistance of the winding II of Q¹, the relay Q² cannot operate, and at its contacts 21^{a2} and 22^{a2} the switching through of the incoming line 1 is prevented.

In the manner described above connections between any other incoming and outgoing lines are set up and the connecting up of some other incoming or outgoing line to the connection set up is prevented. Hence there is no need to describe these operations, as the method of setting up calls other than those described can be directly ascertained from the drawing.

What is claimed is:

1. In a telephone system, a manual switchboard, a plurality of incoming trunks, a plurality of outgoing trunks, keys at said switchboard for connecting any one of said incoming trunks to any one of said outgoing trunks, and means automatically operative responsive to the establishment of such a connection by the operation of one of said keys for preventing the connection of any other incoming trunk to the outgoing trunk in use and for preventing the incoming trunk in use from being connected to any other outgoing trunk by the operation of any one of the other of said keys.

2. In a telephone system, a manual switchboard, a plurality of incoming trunks, a plurality of outgoing trunks, separate keys at said switchboard for connecting any one of said incoming trunks to any one of said outgoing trunks, means operative responsive to the actuation of one of said keys, thereby connecting a certain outgoing trunk to a certain incoming trunk, for preventing the connection of any other incoming trunk to the

connected outgoing trunk and for preventing the connected incoming trunk from being connected to any other outgoing trunk upon the actuation of any one of the other keys.

5. 3. In a telephone system, a manual switchboard, a plurality of incoming trunks, a plurality of outgoing trunks, keys at said switchboard for connecting any one of said incoming trunks to any one of said outgoing trunks, 10 means automatically operative responsive to the actuation of one of said keys for preventing the actuation of any one of the other of said keys from connecting any other incoming or outgoing trunk to either of the two 15 trunks connected by the actuation of said one of said keys.

4. In a telephone system, a manual switchboard, a plurality of incoming trunks, a plurality of outgoing trunks, keys at said switchboard for connecting any one of said incoming trunks to any one of said outgoing trunks, and separate means individual to each incoming trunk, each separate means being operative when the associated incoming trunk is 25 connected to an outgoing trunk by the actuation of one of said keys, for preventing any other incoming trunk from being connected to said outgoing trunk by the actuation of any one of the other of said keys.

30 5. In a telephone system, a manual switchboard, a plurality of incoming trunks, a plurality of outgoing trunks, keys at said switchboard for connecting any one of said incoming trunks to any one of said outgoing trunks, separate means individual to each incoming trunk, each separate means being operative when the associated incoming trunk is connected to an outgoing trunk, by the actuation of one of said keys, for preventing 35 any other incoming trunk from being connected to said outgoing trunk by the actuation of any one of the other of said keys, and separate means individual to each outgoing trunk, each separate means being operative 40 when the associated outgoing trunk is connected to an incoming trunk by the actuation of one of said keys, for preventing any other outgoing trunk from being connected to said incoming trunk by the actuation of 45 any one of the other of said keys.

50 6. In a telephone system, a manual switchboard, a plurality of incoming trunks, a plurality of outgoing trunks, keys at said switchboard for connecting each of said incoming trunks to a different outgoing trunk at the same time, means for preventing the simultaneous connection of two incoming trunks to the same outgoing trunk by the actuation of any two of said keys, and means for preventing the simultaneous connection of two outgoing trunks to the same incoming trunk by the actuation of any two of said keys.

65 7. In a telephone system, a manual switchboard, a plurality of trunks, a plurality of lines, keys at said switchboard for connect-

ing any trunk with any line, there being as many separate keys associated with each trunk as there are lines, a test relay individual to each trunk, a test conductor individual to each line, normally open contacts 70 in each trunk controlled by the associated test relay, means for operating the test relay of a trunk when said trunk is connected to a line by the operation of the corresponding key, and means controlled by said test relay 75 for placing a guarding potential on the test conductor of said line for preventing the operation of the test relay of a second trunk when the key for connecting said second trunk to said line is operated.

80 8. In a telephone system, a manual switchboard, a plurality of trunks, a plurality of lines, keys at said switchboard for connecting any trunk with any line, there being as many separate keys associated with each trunk as 85 there are lines, a test relay and a test conductor individual to each line, a test relay and a test conductor individual to each trunk, normally open contacts in each trunk and in each line controlled by the associated test relays, means for operating the test relay of a trunk and the test relay of a line when said trunk is connected to said line by the actuation of the corresponding key, means controlled by the actuated trunk test relay for 90 placing a guarding potential on the test conductor of the connected line for preventing the operation of the test relay of a second trunk when the key for connecting such second trunk to said line is actuated, and means 95 controlled by the actuated line test relay for placing a guarding potential on the test conductor of the connected trunk for preventing the operation of the test relay of a second line when the key for connecting such second 100 line to the connected trunk is actuated.

105 9. In a telephone system, incoming trunks, outgoing trunks, a multiple for each trunk normally disconnected from the trunk, keys for connecting the multiple of any incoming 110 trunk with the multiple of any outgoing trunk, a test relay for each incoming trunk for connecting the trunk to its multiple, a test relay for each outgoing trunk for connecting the trunk to its multiple, and circuit 115 connections such that when any one key is operated to connect the multiple of a certain incoming trunk with the multiple of a certain outgoing trunk, the test relay of that certain incoming trunk and the test relay of that certain outgoing trunk are operated.

120 10. In a telephone system, incoming trunks, outgoing trunks, a multiple for each trunk normally disconnected from the trunk, keys for connecting the multiple of any incoming 125 trunk with the multiple of any outgoing trunk, a test relay for each incoming trunk for connecting the trunk to its multiple, a test relay for each outgoing trunk for connecting the trunk to its multiple, circuit connections 130

such that when any one key is operated to connect the multiple of a certain incoming trunk with the multiple of a certain outgoing trunk, the test relay of that certain incoming 5 trunk and the test relay of that certain outgoing trunk are operated, and means controlled by the operated test relay of the connected outgoing trunk for preventing the operation of the test relay of any other outgoing 10 trunk by the operation of the key which connects the multiple of the connected incoming trunk with the multiple of the said any other outgoing trunk.

11. In a telephone system, incoming trunks, 15 outgoing trunks, a multiple for each trunk normally disconnected from the trunk, keys for connecting the multiple of any incoming trunk with the multiple of any outgoing trunk, a test relay for each incoming trunk 20 for connecting the trunk to its multiple, a test relay for each outgoing trunk for connecting the trunk to its multiple, circuit connections such that when any one key is operated to

connect the multiple of a certain incoming trunk with the multiple of a certain outgoing 25 trunk, the test relay of that certain incoming trunk and the test relay of that certain outgoing trunk are operated, means controlled by the operated test relay of the connected incoming trunk for preventing the operation 30 of the test relay of any other incoming trunk by the operation of the key which connects the multiple of the connected outgoing trunk with the multiple of the said any other incoming trunk, and means controlled by the 35 operated test relay of the connected outgoing trunk for preventing the operation of the test relay of any other outgoing trunk by the operation of the key which connects the multiple of the connected incoming trunk with the multiple of the said any other outgoing 40 trunk.

In witness whereof, I hereunto subscribe my name this 8th day of April, A. D. 1926.

MAX LANGER.
